BALLAST WORKING IMPLEMENT

Filed Oct. 28, 1935

UNITED STATES PATENT OFFICE

2,137,842

BALLAST WORKING IMPLEMENT

Corwill Jackson, Ludington, Mich.

Application October 28, 1935, Serial No. 46,988

5 Claims. (Cl. 104—13)

The main objects of this invention are:

First, to provide a ballast working tool of high frequency vibration for the purpose of loosening ballast or tamping between and under railroad ties and/or "skeletonizing" the same.

Second, to provide an implement of the type described having reversible blades which are also adjustable with respect to supporting means therefor.

10 Third, to provide a tool for use in connection with ballast loosening or tamping operations, which is characterized by the novel construction thereof.

15 Fourth, to provide a ballast working implement which is extremely efficient and simple in operation.

20 Objects relating to details and economies of my invention will appear from the description to follow. The invention is defined and pointed out in the claims.

Preferred embodiments of my invention are illustrated in the accompanying drawing in which:

25 Fig. 1 is a perspective view of a ballast working implement embodying features of my invention.

Fig. 2 is a fragmentary view in side elevation, illustrating my improved implement in operative relation with respect to ballast between the ties of a railroad track.

30 Fig. 3 is an enlarged detail view in perspective of one of the blades embodied in my invention.

Fig. 4 is a perspective view of a modified tool.

Fig. 5 is a fragmentary elevational view of a modified form of my device, illustrating its position in use in a ballast tamping operation.

35 Fig. 6 is a bottom plan view of the tool employed in the modification of Fig. 5.

Referring to the drawing, reference numerals 1 and 2 indicate respectively a railway tie and track. The reference numeral 3 indicates ballast in the form of crushed rock placed between and under the ties as a foundation or bed for the same.

40 It has been found that the voids between the rocks gradually fill with clay, cinders and other fine particles of foreign matter which become cemented, with the result that proper drainage through the rock voids is prevented. Accordingly, it is necessary to clean this ballast about once each three years. In railway circles, this operation as ordinarily performed is termed "skeletonizing" the track, and heretofore it has consisted in a manual loosening of the cemented material between the ties with blades, shoveling it out of the space between the adjacent ties, cleaning the

same, and returning the cleaned rock to the tie "crib". This is an expensive operation and many devices and machines have been tried to reduce the cost thereof. I have found that the device of my invention is extremely efficient for this 5 "skeletonizing" purpose or for loosening the ballast without removing it (which is termed "bleeding"), yet it is simple in construction.

My improved ballast working implement comprises a handle 4, a vibrating motor 6, a resilient 10 blade-like shank 7, and a plurality of blades or picks 8 which are held in operative relation on the holder. As clearly shown in Fig. 3, blades 8 are formed to provide a pointed working end 9 and a flatwise tapered end 10. Cooperating with 15 shank 7 to hold blades 8 in fixed relation thereto, I provide a pair of plates 11, 12 at either side of shank 7, blades 8 being placed between the shank and plate 11. Plate 12 is angled in cross section to provide a stop or pusher member 13 and bolts 20 14 extend through plates 11 between blades 8 and through shank 7 and plate 12 to clamp the blades in operative position. Nuts 15 cooperate to tighten the assembly. By the above described provisions, it will be seen that I have produced 25 a tool embodying adjustable blades 8 which may be placed in any desired position with respect to shank 7 and clamped thereto. Likewise, blades 8 30 may, if desired, be reversed so that either of the working ends 9 and 10 is available. Stop 13, 30 as is shown in Fig. 2, acts as a pusher element to urge the ballast out from between ties 1.

In operation, the tool just described is vibrated transversely or orbitally by high frequency vibrations imparted to the same by motor 6 which 35 includes a rotating eccentric element or unbalancing weight 16 on the shaft 17 thereof, with the result that sifting action is imparted to the picks or blades 8. The handle 4 is flexibly attached to the motor 6 by means of a frame made 40 up of members 18, 19 connected and spaced by cross members 20, 21. Adjustable with respect to cross piece 20 on frame members 18, 19, I mount a slide 22 carrying a cross rod (not shown). Likewise, adjacent cross piece 21 a similar cross 45 rod 23 is fixedly mounted in members 18, 19. A support member 24 of flexible material is looped around cross rod 23 and the cross rod carried in slide 22, and motor 6 is suitably attached to the support member. Frame members 18, 19 are 50 suitably rigidly attached to handle 4.

At the end thereof, opposite support member 24, motor 6 carries a pair of plates 25, 26 between which is received shank 7 mounting the tool of my invention. Bolts 27 rigidly secure plates 25, 55

26 and shank 7 in working position. A conduct-
ing cable 28 is connected to motor 6 in conven-
tional manner for supplying operating current
thereto.

5 In Fig. 4, I show a modification of a tool suit-
able for use in connection with the vibrating
means of high frequency just described, comprising
shank 7, plates 25, 26 and a blade 29 extend-
ing the width of shank 7 and provided with a plu-
rality of pointed picks or tines 30. Blade 29 is
10 secured to shank 7 by bolts 31 or other suitable
securing means, preferably of a type to allow the
removal of the pick from the blade.

15 Alternatively, I may employ in connection with
my device blades such as are illustrated in Figs.
5 and 6 having one end of the same squared to
provide blunt tamping surfaces 81. The blades
of this modification are mounted on the blade-
like shank 7 in the same manner as are the
20 blades 8 hereinbefore described. The device illus-
trated in Figs. 5 and 6 may be employed in tamping
or compacting gravel to a suitable degree
once the track has been "skeletonized." In such
25 employment of the blades 8 having tamping sur-
faces 81, it is obvious that the pusher element
13 may be omitted. By combining the pointed
ballast loosening ends 9 and the blunt tamping
ends 81 on a single blade 8, it will be obvious
30 that I have provided a tool element of high
utility, since the pointed ends may be utilized
to loosen gravel which has become cemented,
after which operation the blade may be reversed
and the gravel properly tamped to give the nec-
essary firmness of foundation for the ties.

35 In all the modifications of my invention, I
contemplate employing a shank 7 of a resilient
material since I find that the effectiveness of my
implement is improved by such a feature.

40 It is believed that from the above description
the operation of my device is clear. My imple-
ment is used in so-called "skeletonizing" opera-
tions and where new ballast is to be inserted be-
tween and under ties. The adjustable feature
45 of the blades permits the device to penetrate any
desired depth of ballast, while the reversible fea-
ture thereof adapts it for ready use in connec-
tion with differing conditions encountered and
for differing operations. It has been found that
the high frequency vibration imparted to the
50 blades not only loosens the ballast but tends to

shake the particles of cement-like material from
the rock and thus performs a very good job of
cleaning without removal of the material from
the "crib" or space between adjacent ties.

The machine is also highly efficient for tamping 5
rock ballast under loose ties particularly if
the ballast is badly cemented together with clay
and other foreign material. The relatively nar-
row multiple blades effectively settle and com-
pact the ballast under the tie. The machine may 10
be easily manipulated to accomplish both the
breaking up and tamping action.

I have illustrated and described my improve-
ments in embodiments which I have found very
practical. I have not attempted to illustrate or 15
describe other embodiments or adaptations as
it is believed this disclosure will enable those
skilled in the art to embody or adapt my im-
provements as may be desired.

Having thus described my invention, what I 20
claim as new and desire to secure by Letters Pat-
ent, is:

1. A ballast working tool comprising a shank,
a plurality of reversible and adjustable blades
mounted thereon, and means for clamping said 25
blades to said shank comprising an angled pusher
element extending upwardly from said shank.

2. A ballast working tool comprising a shank,
a plurality of adjustable blades mounted thereon,
and means for clamping said blades to said 30
shank comprising an angled pusher element ex-
tending upwardly from said shank.

3. A ballast working tool comprising a shank,
a plurality of blades mounted thereon, means
for clamping said blades to said shank, and an 35
angled pusher element mounted on said shank
and extending transversely thereof.

4. A ballast working tool comprising a shank,
a plurality of blades mounted thereon, each blade
having a plurality of working ends of differ- 40
ing character, and means for removably clamping
said blades to said shank, permitting the blades
to be reversed.

5. A ballast working tool comprising a shank,
a plurality of blades mounted thereon, each blade 45
having a plurality of working ends, and means
for removably clamping said blades to said shank,
permitting the blades to be reversed.

CORWILL JACKSON. 50
